R. C. MATSON,
PHOTOGRAPHIC PLATE HOLDER,
APPLICATION FILED MAR. 23, 1918.

1,358,090.

Patented Nov. 9, 1920.

Inventor:
Ralph C. Matson.

by J. Gleisler
Atty.

UNITED STATES PATENT OFFICE.

RALPH CHARLES MATSON, OF PORTLAND, OREGON.

PHOTOGRAPHIC-PLATE HOLDER.

1,358,090.

Specification of Letters Patent.

Patented Nov. 9, 1920.

Application filed March 23, 1918. Serial No. 224,278.

To all whom it may concern:

Be it known that I, RALPH C. MATSON, a citizen of the United States, and a resident of the city of Portland, county of Multnomah, State of Oregon, have invented a certain new and useful Improvement in Photographic-Plate Holders, of which the following is a specification.

The object of my invention is to obtain a convenient and inexpensive holder for negatives and other photographic plates, and particularly to make my holder adapted for holding plates of greatly varying sizes; also to make the whole structure of sufficient 15 stiffness so as to prevent any breaking strain on the larger sized plate when held by my holder and the latter is being handled.

My invention further has for its object to provide the sides of the holder with laterally projectable arms by which one end of the holder may be supported while the other end is immersed in a sink or trough while working on a negative; and also providing one end of the frame with means for suspending the same while drying.

The construction of my holder is fully illustrated in the accompanying drawings, in which:

Figure 1 is a top view;

30 Fig. 2 is a section of the frame on the line 2-2 of Fig. 1, except that the supporting arms are arranged in their folded position.

Fig. 3 is a perspective section on the line 3-3 of Fig. 1;

35 Fig. 4 is a sectional detail on the line 4-4 of Fig. 1;

Fig. 5 is a sectional detail on the line 5-5 of Fig. 1, looking in the direction pointed by the arrow 5; and

40 Fig. 6 is a fragmental view of that end of the slide provided with a holding groove for receiving one side of the plate; this figure illustrates how the plate is held in place on the frame.

45 The frame comprises side pieces *a*, *a*, which are folded so as to provide grooves, as illustrated at *a'* in Fig. 3. One end of the frame is connected by a transverse piece *b* shaped to provide a plate-holding groove *c*. The opposite ends of the frame sides are connected by a cross-piece *d*, provided with a hook *e* for suspending the frame. The cross-piece *d* may be an integral part of the frame sides.

55 The grooves *a'* of the sides, *a*, are adapted to hold a slide *f*. This slide is preferably

made of a single sheet of metal, cut as at *h*, so as to provide elongate shoe-portions *g*, *g'*, bearing in said grooves *a'*; and the part *i* between said cuts is folded back upon itself, and formed with a lip *j*, as shown in Fig. 3, to provide a plate-holding groove *j'* facing the plate-holding groove *c* of the frame. The shoe-portions *g*, *g'*, are adapted to project a substantial distance beyond the body of the slide *f*, so as to give rigidity to the latter, and incidentally stiffening the frame-sides, thereby minimizing any danger of cracking a larger-sized plate held by my plate-holder, in the handling of the latter.

The plate is secured in place between the plate holding grooves *c*, *j'*, as illustrated in Fig. 2, and as will be noted the plate holding grooves are located above the plane of the upper faces of the frame sides, and in this way my holder is adapted for holding a plate *p* projecting over the frame sides, as shown in Fig. 6.

In order to have means for supporting one end of my holder in a sink or trough, I provide the frame-sides, *a*, with foldable laterally projectable arms *k*, *k*, pivoting on pivots *m*. And in order to limit the movement of the arms *k* when extended, I provide stops *n* on the frame sides, and also prefer to provide the arms *k* with stud pins *o*, which may be snapped into cavities *o'* therefor provided in the frame sides, as shown in Fig. 2, when the arms *k* are to be arranged parallel with the frame sides.

In order to facilitate the handling of the slide, I provide the same with a finger-piece *q*.

I claim:

1. As a photo-plate holder, a rectangular metal frame comprising sides folded to form grooves for a slide and transverse pieces connecting the ends of the sides, one of said transverse pieces being provided with a plate holding groove, a slide bearing in said slide grooves, the slide being made of a single sheet of metal and comprising shoes, the sheet being slotted adjacent to and parallel with said shoes, the transverse body-piece intermediate the slits being folded back on itself, and the free edge of such body-piece being formed into a plate holding groove facing that of the frame.

2. As a photo-plate holder, a rectangular metal frame comprising sides folded to form grooves for a slide, and transverse pieces

- connecting the ends of the sides, one of said transverse pieces being provided with a plate-holding groove, a slide bearing in said slide grooves, the slide being made of a single sheet of metal and comprising shoes, the sheet being slitted adjacent to and parallel with said shoes, the transverse body-piece intermediate the slits being folded back on itself and the free edge of such body-piece being formed into a plate-holding groove facing that of the frame, and the shoes projecting a substantial distance beyond either side of the transverse body-piece.
3. As a photo-plate holder, a rectangular metal frame comprising sides folded to form grooves for a slide and transverse pieces connecting the ends of the sides, one of said transverse pieces being provided with a plate holding groove, a slide bearing in said slide grooves, the slide being made of a single sheet of metal and comprising shoes, the sheet being slitted adjacent to and parallel with said shoes, the transverse body-piece intermediate the slits being folded back on itself, and the free edge of such body-piece being formed into a plate holding groove facing that of the frame, and the plate-holding grooves lying in a plane above that of the sides.
4. As a photo-plate holder, a rectangular metal frame comprising sides stiffened by being folded upon themselves to form a double thickness, and also formed with flanges spaced apart from said folds to provide grooves for a slide, and transverse pieces connecting the ends of the sides, one of said transverse pieces being provided with a plate holding groove, a slide bearing in said slide grooves, the slide being made of a single sheet of metal and comprising shoes, the sheet being slitted adjacent to and parallel with said shoes, the transverse body-piece intermediate the slits being folded back on itself and the free edge of such body-piece being formed into a holding groove facing that of the frame, and the plate-holding grooves lying in a plane above that of the sides.
5. As a photo-plate holder, a rectangular metal frame comprising sides stiffened by being folded upon themselves to form a double thickness, and also formed with flanges spaced apart from said folds to provide grooves for a slide, and transverse pieces connecting the ends of the sides, one of said transverse pieces being provided with a plate holding groove, a slide bearing in said slide grooves, the slide being made of a single sheet of metal and comprising shoes, the sheet being slitted adjacent to and parallel with said shoes, the transverse body-piece intermediate the slits being folded back on itself and the free edge of such body-piece being formed into a plate holding groove facing that of the frame, the plate-holding grooves lying in a plane above that of the sides, the shoes projecting a substantial distance beyond either side of the transverse body-piece, and lateral arms on the frame sides.
6. As a photo-plate holder, a rectangular metal frame comprising sides stiffened by being folded upon themselves to form a double thickness, and also formed with flanges spaced apart from said folds to provide grooves for a slide, and transverse pieces connecting the ends of the sides, one of said transverse pieces being provided with a plate-holding groove, a slide bearing in said slide grooves, the slide being made of a single sheet of metal and comprising shoes, the sheet being slitted adjacent to and parallel with said shoes, the transverse body-piece intermediate the slits being folded back on itself and the free edge of such body-piece being formed into a plate-holding groove facing that of the frame, the plate-holding grooves lying in a plane above that of the sides, the shoes projecting a substantial distance beyond either side of the transverse body-piece, a take-hold on the transverse body-piece of the slide, means on the frame for suspending the same, and foldable lateral arms on the frame sides.
7. As a plate holder, a rectangular metal frame comprising side pieces provided with grooves for holding a slide and transverse end pieces, one of said end pieces being provided with a plate-holding groove, a slide bearing in said groove comprising shoes sliding in said slide grooves, and an intermediate transverse body-piece provided with a holding groove facing the plate holding groove of the frame-end, and the plate-holding grooves lying in a plane above that of the sides.
8. As a plate holder, a rectangular metal frame comprising side pieces provided with grooves for holding a slide and transverse end pieces, one of said end pieces being provided with a plate-holding groove, a slide bearing in said groove comprising shoes sliding in said slide grooves, and an intermediate transverse body-piece provided with a plate holding groove facing the plate-holding groove of the frame-end, plate-holding grooves lying in a plane above that of the sides, and laterally projectable arms on the frame sides.

RALPH CHARLES MATSON.
